UNITED STATES PATENT OFFICE.

CLOICE B. BAKER, OF ST. LOUIS, MISSOURI, ASSIGNOR OF ONE-HALF TO WILLIAM BAWDEN, OF ST. LOUIS, MISSOURI.

SUPPORT FOR RUNNING-BOARDS FOR VEHICLES.

1,339,379.

Specification of Letters Patent.

Patented May 4, 1920.

Application filed January 12, 1920. Serial No. 350,865.

To all whom it may concern:

Be it known that I, CLOICE B. BAKER, a citizen of the United States, residing at St. Louis, State of Missouri, have invented certain new and useful Improvements in Supports for Running-Boards for Vehicles, of which the following is a full, clear, and exact description, reference being had to the accompanying drawings forming a part hereof.

The present invention is directed to improvements in supports for running boards for locomotives, box cars, and vehicles generally, having special application to locomotives however because of its eminent adaptation to this type of vehicle. As well known to those skilled in the art, the usual manner of mounting a locomotive running board is to secure to the outer shell of the locomotive by means of stud-bolts a series of angle brackets, the horizontal arms of which form the immediate supporting members for the board, the latter being fastened to the bracket arms by means of carriage bolts or in any other suitable mechanical manner. It frequently happens that in the switching of engines, or where engines have frequent occasion to pass one another as at railroad terminals, an engine is often side-swiped by another engine or car, the side-swipe usually tearing off the running board. In the majority of these accidents the stud-bolts by which the brackets are secured to the boiler shell are torn from the shell, leaving openings through which the hot water and steam (usually at a pressure of two hundred pounds or more to the square inch) are allowed to escape, thereby not only enveloping the engine in a cloud of steam, but often making it impossible for the engineer and fireman to escape when they are usually scalded to death. The main object sought by the present invention is to provide a support for the running board which will insure against the tearing out of the stud-bolts secured to the boiler shell, at the same time providing means for flexibly supporting the board so that the same may yield if side-swiped by another car or engine, the flexible character of the support removing the strain which would otherwise pull the securing

bolts from their moorings in the shell. A further object is to provide an installation in which the brackets forming the flexible support will not distort when the engine is side-swiped, thereby making it easy to repair the engine and cutting down the cost of repairs. The advantages of the invention will be more fully and clearly apparent from the following detailed description in connection with the accompanying drawings in which—

Figure 1 represents a perspective of the rear end of a locomotive boiler showing my invention applied thereto; Fig. 2 is a transverse vertical section through the fire box showing end views of the running boards; Fig. 3 is an enlarged side elevation of one of the supporting brackets, the boiler shell wall and running board being shown in cross section; Fig. 4 is a top plan of the bracket shown in Fig. 3; Fig. 5 is a vertical sectional detail on the line 5—5 of Fig. 4; Fig. 6 is a front elevation of the casting which supports the bracket carrying the running board; Fig. 7 is a side elevation of the casting showing the manner of righting or leveling the same to conform to the curvature of the boiler wall; and Fig. 8 is a bottom plan of the bracket, the same being broken away at an intermediate point of its length.

Referring to the drawings, B, represents the shell of the boiler, F, the fire box, W, the water legs on the sides of the fire-box, and C, the cab, as well understood in the art. Disposed along the outer sheets of the water legs, and along the shell of the boiler are a series of bracket-supporting castings each comprising a body portion or plate 1 terminating at the top in a rearwardly projecting flange or "chipping strip" 2 extending the full width of the plate, a second rearwardly projecting, centrally disposed narrow chipping strip or leg 3 being formed along the bottom edge of the plate, said leg 3 being of greater length than the flange 2 and extending rearward of the plate beyond the free edge of the flange. Disposed on the front side of the plate is a socket 4 extending the full height of the plate, the latter being provided on opposite sides of the socket with holes o for the passage therethrough of the

stud bolts 5 leading from the boiler, the stud in Fig. 3 being shown in connection with the outer sheet of the water-leg W. The socket 4 of each casting receives the 5 pivot pin or stud 6 leading from the boss 7 at the fulcrum end of a bracket arm 8, the top of the casting 1 engaging the annular shoulder s formed by the bottom face of the boss around the base of the pin, whereby the 10 bracket arm becomes hingedly or pivotally supported by the casting.

It will be remembered that the flange 2 and leg 3 were referred to as "chipping strips". The function served thereby is best 15 brought out in Fig. 7. The casting 1 when applied to the shell of the boiler or to the water-leg on the side of the fire-box is placed with the members 2, 3, against the boiler wall. Should the outer curvature of this 20 wall be such as to cause the casting to tilt from a truly vertical position, or from one which will incline the upper surface of the casting away from the horizontal, the workman simply chips off the necessary amount 25 of metal from either the flange 2 or leg 3 to permit the casting to assume the proper position for supporting the bracket arm 8 in a truly horizontal plane. In the figure referred to the dotted position of the casting 30 is the correct position, it being necessary to chip off from the flange 2 shown in full, a strip of the width indicated by the dotted portion a to permit the casting to be tilted from its inclined full line position to 35 its righted or truly vertical dotted position, it being necessary of course to dispose the top supporting surfaces of the several castings in a horizontal plane to hold the bracket arms which carry the running board 40 in a horizontal position. The running board 9 (shown herein in two sections) is secured to the bracket arms 8 by means of carriage bolts 10 as well understood in the art. The rear end of the board or that supporting 45 the cab C is wider than the portion opposite the shell B of the boiler, an offset d being formed in the board for that purpose. Obviously, the bracket arms 8 supporting the narrower portion of the board are 50 shorter than the bracket arms leading from the fire box walls and supporting the rear wide end of the board (Fig. 1).

In practice, after the several castings 1 have been secured to the boiler, the pivot 55 pins 6 of the several bracket arms are inserted into the sockets 4 of the castings and swung parallel to one another to a position at right angles to the boiler wall, after which the running board is deposited on the 60 bracket arms and secured thereto by the bolts 10. In case of a side-swipe, the most serious damage is a splintering or tearing of the board from the bracket arms, the pivotal connections between the latter and the 65 castings 1 causing a deflection or yielding

of the bracket arms as a result of the shock due to the impact of the side-swipe. Under those circumstances there is absolutely no danger of the tearing out of the stud bolts 5 from their moorings in the boiler walls, 70 and consequently no possibility of releasing the steam and hot water from the boiler. There is therefore no likelihood of the engineer or fireman being scalded by escaping steam. Obviously, I may in a measure depart 75 from the details of construction here shown without departing from the nature or spirit of the invention.

Having described my invention what I claim is—

1. In combination with a vehicle, a series of fixed supports on the side thereof spaced suitable distances apart, brackets leading therefrom and disposed in hinged relation thereto about substantially vertical axes, 85 and a running board secured to said brackets.

2. In combination with a vehicle, a series of fixed supports on the side thereof spaced suitable distances apart, brackets leading 90 therefrom and disposed in hinged relation thereto about substantially vertical axes, a running board mounted on the brackets, and means for fastening the board to the brackets.

3. In combination with a vehicle, a series of fixed supports on the side thereof spaced suitable distances apart and provided with vertically disposed sockets, brackets provided at one end with pivot pins or studs 100 loosely received by said sockets, a running board supported by the several brackets, and bolts for securing the board to the brackets.

4. In combination with a locomotive boiler, a series of socket plates secured there- 105 to along the sides thereof, bracket arms provided with vertically disposed pins or studs loosely received by the sockets and projecting outwardly from the boiler, a running board deposited on the bracket arms, and 110 bolts for securing the board to said arms.

5. A bracket-supporting member for running boards for locomotives comprising a plate provided on one side with a socket, a chipping strip at one end of the plate on 115 the side opposite the socket extending substantially the full width of the plate, and a chipping strip or leg at the opposite end and of greater length than the first mentioned chipping strip.

6. A bracket-supporting member for running boards for engines, comprising a plate provided on one side with a centrally disposed socket, a chipping strip extending the width of the plate at one end thereof on 125 the side opposite from the socket, a second chipping strip at the opposite end of the plate disposed opposite the socket and having a length such as to project a greater distance from the face of the plate than 130

the first mentioned chipping strip, the plate being provided with bolt holes on opposite sides of the socket.

7. In combination with a fixed support, a series of bracket arms mounted hingedly thereto about substantially vertical axes and projecting in the same general direction therefrom, and a running board se-

cured to said series of arms and disposed to one side of the hinge axes of the arms. 10

In testimony whereof I affix my signature, in presence of two witnesses.
